UNITED STATES PATENT OFFICE.

HARRY B. RODGERS, OF CHAMBERSBURG, PENNSYLVANIA.

CONTAINER FOR SANITARY SHAVING-BRUSHES.

1,168,423.

Specification of Letters Patent.

Patented Jan. 18, 1916.

Application filed November 24, 1914. Serial No. 873,759.

To all whom it may concern:

Be it known that I, HARRY B. RODGERS, a citizen of the United States, residing at Chambersburg, in the county of Franklin, 5 and State of Pennsylvania, have invented certain new and useful Improvements in Containers for Sanitary Shaving-Brushes, of which the following is a specification.

It is the aim of the present invention to 10 provide a sanitary shaving brush and container therefor.

It is one object of the invention to provide a shaving brush which may be manufactured at a low cost and placed upon the market 15 ready for instant use, and adapted for the production of a lather when properly moistened.

More specifically, the invention contemplates the provision of a brush, the applying 20 portion of which is so treated with a saponaceous substance, that the brush will not be required to be applied to a cake of soap.

Another object of the invention is to provide a shaving brush which, while it may 25 be used as conveniently as the ordinary brush, will be so inexpensive to manufacture that it may be thrown away after being used but once.

Another object of the invention is to provide a sanitary shaving brush possessing the 30 properties and advantages above mentioned and further to provide for the brush a container which will effectually protect the applying portion of the brush from contamination 35 and which may be readily removed from the brush when it is desired to use the latter.

A further object of the invention is to provide a novel and extremely simple brush 40 construction and a novel and extremely simple and inexpensive container therefor.

In the accompanying drawings: Figure 1 is a perspective view of the article embodying 45 the present invention. Fig. 2 is a similar view, illustrating the container for the brush partly opened. Fig. 3 is a vertical transverse sectional view through the container, the brush being shown in elevation. Fig. 4 is a sectional view taken in a vertical plane 50 at right angles to the plane of Fig. 3. Fig. 5 is a perspective view of the brush removed and ready for use. Fig. 6 is a view similar to Fig. 3 illustrating a slight modification of the invention.

Corresponding and like parts are referred 55 to in the following description and indicated

in all the views of the accompanying drawings by the same reference characters.

Generally stated, the article embodying the present invention comprises a tuft of fibrous material, the applying portion of which has been treated with a saponaceous substance, associated with a container constructed to house the tuft comprising the brush and adapted to be torn open when it is desired to remove and use the brush. 60 Inasmuch as it is essential that the brush be of such construction and material as to be inexpensive to manufacture, I prefer to employ in the manufacture of the brush a tuft of Manila fibers, although of course, if 65 desired, fibrous material of a more expensive nature may be employed.

In the drawings, the numeral 1 indicates a tuft of such fibers, the fibers comprising the tuft being tightly bound together at one 70 end of the tuft by means of a band 2 of paper or any other suitable material. While it is preferable to employ a band, as illustrated in the drawings, the fibers may, if desired, be bound by cord, wire, or, in fact, 75 in any suitable manner and with any suitable material, and, in fact, if desired, the end of the tuft may be immersed in some binding agent having the property of hardening and in this manner securing the 80 fibers together. The end of the tuft just described is of course the handle end and the opposite end of the tuft, indicated by the numeral 3, constitutes the applying portion of the brush. As before stated, the applying portion of the brush is treated with a saponaceous substance and this may be accomplished either by dipping the said applying portion in a soap solution or liquid soap composition, and then removing the 85 brush therefrom and allowing the same to dry, or a suitable soap powder may be dusted or otherwise distributed among the fibers comprising the applying portion of the brush. In fact, there are numerous ways in 90 which a saponaceous substance could be applied to the said portion of the brush and I am therefore not to be limited to the precise means herein described. A brush treated with the liquid soap composition, as above 95 mentioned, is shown in Figs. 3, 4 and 5 of the drawings, and Fig. 6 illustrates a brush to which a suitable soap powder has been applied.

The container for the brush above de- 110

scribed is preferably made of paper, although it may be found desirable to employ some other material for this purpose, and this container is made up from a blank of 5 any suitable or convenient form or outline, and in its completed form is substantially in the nature of a bag of trapezoidal outline. The container is indicated in general by the numeral 4, the closed lower end 10 thereof being indicated at 5, the receiving upper end at 6, and the side edges at 7 and 8. By reference to Fig. 2 it will be observed that the upper and lower ends of the container are parallel and that the side 8 ex- 15 tends on a line at right angles to the said upper and lower ends, the side edge 7 being non-parallel to the side 8 and the container being of less width at its upper or receiving end than at its closed lower end. A quan- 20 tity of any suitable adhesive is applied, as at 9, at the upper end of the container, to the inner surface of the front and back thereof, and after the brush has been introduced into the container, this adhesive area 25 may be moistened and the mouth or receiving end of the container may be closed tightly about that portion of the brush surrounded by the band 2 so that the inner surfaces of the front and back of the container 30 at the mouth thereof will adhere to the said band in the manner shown in Fig. 2 of the drawings. It will be apparent by reference to the said Fig. 2, that when the mouth of the container is closed about the brush, the 35 handle portion of the brush is disposed at that side of the mouth adjacent the inclined side 7 of the container. It will also be observed that the inner surfaces of the front and back of the container at the mouth 40 thereof, adhere to each other laterally beyond the portion of the mouth which surrounds the handle portion of the brush. To the outer side of the front of the container, at the mouth thereof, there is applied, as 45 indicated at 10, a quantity of adhesive, and

after the container has been assembled with the brush in the manner above described, the portion of the body of the container lying laterally beyond the portions comprising the brush is folded along a diagonal line, indicated approximately at 11, and in the manner illustrated clearly in Fig. 1 of the drawings, the adhesive area 10 being moistened whereby to hold the portion folded as stated. 50

55

It will be understood that the article is to be placed upon the market in the condition shown in Fig. 1 of the drawings, and when it is desired to use the brush, the portion 12 of the container is pulled back, as shown in 60 Fig. 2, of the drawings and is then torn off, whereupon the remaining portion of the container may be readily removed from the brush.

Having thus described the invention, what 65 is claimed as new is:

As a new article of manufacture, a sanitary container for a shaving brush of substantially trapezoidal form, the container having its mouth located at its minor end 70 and its bottom at its major end and having one side substantially at right angles to the said bottom, the walls of the container at the mouth thereof being adapted to be united subsequent to the introduction of the 75 bristle end of the brush into the container and the said walls at the said mouth being arranged to have their ununited portions surround the shank of the brush, that portion of the container which is laterally disposed with relation to the portion embracing the brush being adapted to be folded over and secured to the said brush embracing portion. 80

In testimony whereof I affix my signature in presence of two witnesses.

HARRY B. RODGERS. [L. S.]
